Primary Examiner—Paula Greene(74) *Attorney, Agent, or Firm*—Banner & Witcoff, Ltd.(57) **CLAIM**

The ornamental design for a headset, as shown and described.

DESCRIPTION

FIG. 1 is a perspective front view of a headset showing my new design;

FIG. 2 is a front view thereof;

FIG. 3 is a right side view thereof;

FIG. 4 is a left side view thereof;

FIG. 5 is a top view thereof;

FIG. 6 is a bottom view thereof; and,

FIG. 7 is a rear perspective view thereof.

The broken line showing of the environmental structure of the headset in the figures is for illustrative purposes only and forms no part of the claimed design.
